(57) **CLAIM**

We claim the ornamental design for a video enhancer, as shown and described.

DESCRIPTION

FIG. 1 is a top view of the video enhancer;
FIG. 2 is a bottom view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a front, right, top perspective view thereof; and,
FIG. 8 is a front, right, bottom perspective view thereof.
The broken lines in the drawings are for illustrative purposes only and form no part of the claimed design.
